Attorney.

UNITED STATES PATENT OFFICE.

JOHN L. SYMONDS, OF DETROIT, MICHIGAN.

FENCE.

SPECIFICATION forming part of Letters Patent No. 390,995, dated October 9, 1888.

Application filed January 30, 1888. Serial No. 262,437. (No model.)

To all whom it may concern:

Be it known that I, JOHN L. SYMONDS, a citizen of the United States, residing at Detroit, county of Wayne, State of Michigan, have 5 invented a certain new and useful Improvement in Fences; and I declare the following to be a full, clear, and exact description of the invention, such as will enable others skilled in the art to which it appertains to make and use 10 the same, reference being had to the accompanying drawings, which form a part of this specification.

My invention consists of the combinations of devices and appliances hereinafter specified, and more particularly pointed out in the 15 claims.

In the drawings, Figure 1 is a view in elevation of a fence embodying my invention. Fig. 2 is a sectional view on line $x-x$. Fig. 3 20 is a sectional view on line $z-z$. Fig. 4 is a separate view of two adjacent picket-braces with the rosette removed; Fig. 5, a separate view of the rosette. Fig. 6 illustrates how the device is adapted for fences on sloping ground.

25 The purpose of my invention is to provide a convenient means for fastening the pickets to the rails in the construction of ornamental wrought-iron fences, which means I will proceed to describe.

30 A represents the pickets and B the rails of a wrought-iron fence.

C represents a brace, preferably of malleable iron, which engages the picket above and below the rail at the points $c-c'$. The brace is 35 provided at its sides with dowel-holes c^2 .

D is a rosette provided on its back with dowel-pins d , adapted to engage within the holes c^2 . The rosette has a central bolt-hole, and a bolt or rivet, E, passes through this hole 40 and a corresponding hole in the rail, and a nut, e , binds the whole together.

The brace C is so shaped that when adjusted upon the picket it does not rest at the sides against the rail, but stands a little off therefrom.

45 Then by tightening the nut e on the bolt the

casting may be sprung toward the rail and so bind the brace firmly against the picket and the picket against the rail, holding the parts securely by friction.

This invention is equally applicable in the 50 construction of fences upon sloping ground, as shown in Fig. 6, it being only necessary to so locate the braces C that the dowel-pins of the intermediate rosette may engage the dowel-holes c^2 , the rosettes being correspondingly 55 rotated to accommodate the inclined arrangement of the braces.

The foregoing affords an exceedingly cheap and simple construction, and the resulting fence is exceedingly strong and substantial. It requires no machine-work upon the pickets or braces, it being only necessary that the rails be punched for the bolts E.

c^3 represents one or more bars, which span the brace C from side to side, being fitted over 65 the picket. They serve to stiffen the brace and to transmit the binding action of the bolts E, not only to the top and bottom of the brace, but also to its middle point, and materially assist to hold the picket in place. 7c

What I claim is—

1. The combination, with the picket-braces C, having dowel-holes c^2 at their sides, of rosette D, provided with corresponding dowel-pins d , and means for securing the rosette to 75 the rails of the fence, substantially as described.

2. The combination, with the fence-pickets, the rails, and braces C, engaging the front of the pickets at $c-c'$, said braces provided with 80 dowel-holes c^2 of rosettes D, with dowels d , and binding bolts and nuts E e , substantially as described.

In testimony whereof I sign this specification in the presence of two witnesses.

JOHN L. SYMONDS.
